UNITED STATES PATENT OFFICE.

LYTTELTON F. MORGAN, OF NEW YORK, N. Y.

KEY.

1,295,351.

Specification of Letters Patent. Patented Feb. 25, 1919.

Application filed August 23, 1918. Serial No. 251,087.

To all whom it may concern:

Be it known that I, LYTTELTON F. MORGAN, a citizen of the United States, residing at 2228 Amsterdam Ave., in the county of New York and State of New York, have invented new and useful Improvements in Keys, of which the following is a specification.

This invention consists in an improvement in keys of the well known "Yale" type, 10 that is, keys cut and stamped of sheet metal and with their blades corrugated on both sides and bitted on one edge.

It frequently happens that keys of this kind break off in the lock, causing much inconvenience and expense. As now constructed, the weakest part of the key is in the blade at the deepest bit, and when a key is broken in the lock, part of the blade remains in and can only be extracted with 20 great difficulty.

I overcome this objection by locating the weakest part of the key, that is, the place where it has the least cross sectional area, in the head or in that portion of the key 25 which does not enter the lock. I do this by providing the blade with an enlargement and uniting this enlargement to the bow by a reduced portion or neck of less cross sectional area than any part of the blade. 30 Thus, if too much force is used in attempting to turn the key in the lock, it will break at that reduced portion or neck and the key can nevertheless be withdrawn by taking hold of the enlargement and, if desired or 35 necessary, can continue to be used, the enlargement serving as the handle or grip.

I am aware that it is not new to provide a weak spot in some kinds of machinery so that the break will be definitely located in 40 the event of too much strain, but I believe I am the first to apply the idea to a key and that the improved construction described and claimed is novel; its utility is obvious.

The invention is, of course, adapted to 45 any style of flat sheet metal key having a bitted blade. Its essential feature is the provision of two handles or grips connected by a neck which constitutes the weakest part of the key. Preferably the first grip is a 50 relatively small enlargement of the blade and the outer one is the usual apertured bow. The enlargement may also have an aperture in it so that the key can be carried on a ring even after the bow has been broken 55 off.

The invention is illustrated in the accompanying drawing.

Figure 1 is an elevation of a key embodying my improvement.

Fig. 2 is an elevation of a key blank 60 equipped with a slightly modified form of the improvement, and

Fig. 3 is an edge view of the blank of Fig. 2.

1 represents the corrugated shank or blade 65 of the key and 2 the bow or handle. 3 is the enlargement at the end of the blade, or, as it may be called, the emergency grip; in Fig. 1, it is provided with the hole 4 to slip on a key ring or attach a tag. 5 is the reduced portion or neck which connects the grips 2 and 3 and which is the weakest point 70 of the key. It must be of less cross sectional area than the blade at the point of the deepest bit 6. In Fig. 1 the neck is of the same thickness as the rest of the key while in Fig. 2 it is shown as of reduced thickness. 75

It will be obvious that the invention is independent of the particular shape and form of the blade and handle; that illustrated is by way of example merely. Any 80 kind of flat key can be provided with the improvement.

Having thus described my invention, what I claim is:

1. A flat key comprising a bitted blade 85 having a widened portion at its base, a bow or grip, and a neck between said widened portion and said bow, the amount of metal in said neck being less than at any part of the blade. 90

2. A flat key comprising a blade provided with bits in its edge, a head or emergency grip on said blade, and a bow united to said head by a neck the cross sectional area of which is less than that of the blade at the 95 deepest bit.

3. In a sheet metal key, the combination with the blade and bow, of an enlargement forming an emergency grip at the base of the blade and a reduced neck uniting said bow to said enlargement, the dimensions of said neck being such that the key will break there if too much force is used. 100

In testimony whereof I have hereunto set my hand.

LYTTELTON F. MORGAN.
